UNITED STATES PATENT OFFICE

CHARLES R. DIEHL, OF DETROIT, MICHIGAN

SAFETY RAZOR

Application filed January 19, 1932. Serial No. 587,473.

This invention relates to improvements in razors and aims, among other things, to provide a razor consisting of relatively few parts which can be simply and quickly taken apart or assembled.

Another object of the invention is to provide a razor wherein a relatively heavy blade may be employed, and wherein simple and effective means are provided for holding the blade in position on its supporting plate, and for holding the latter relative to the handle whether the blade is in the razor or not.

With these and other objects and advantages in view which will become apparent as the specification proceeds, a preferred embodiment of the invention is hereinafter described with the aid of the accompanying drawing, in which:

Figure 1 illustrates a side elevation of the invention,

Figure 2 is a rear view thereof, and

Figure 3 is a front view.

Figure 4 shows a view of the handle on the line 4—4 of Figure 1.

Figure 5 shows a view of the supporting plate on the line 5—5 of Figure 1, and

Figure 6 is a plan of the blade.

Figure 7 is an enlarged detail.

Referring to the drawing, 1 designates a supporting plate which is inclined relative to a shank 2 which extends from its underside substantially centrally of its width and adjacent its rear margin. The front margin of the plate is provided with a plurality of forwardly projecting fingers 3, and on its upper face two opposed projections 4 are formed adjacent opposite sides of the plate intermediately of its length; and again, projecting from the said upper face adjacent its rear margin and intermediately of its width are other projections 14.

5 denotes a blade which is preferably thicker along its rear margin and has recesses 5a formed therein to receive the plate projections 4. The front margin of the blade 5b, which constitutes its cutting edge, rests on or adjacent the outer fingers 3a, and between the latter the front extremity of the plate 1 has its upper face downwardly re-

cessed to provide clearance between the said plate and the cutting edge of the blade 5.

6 denotes a handle against the front face of which the shank 2 rests for the major portion of its length. Adjacent the lower extremity of the handle 6 is a forward projection 7 the upper side of which is substantially V-shaped to receive the correspondingly formed outer extremity of the shank 2. It will also be noted that the V-shaped portions 60 are transversely curved as shown in Figure 3 to prevent independent movement of the coacting surfaces. Integral with the upper extremity of the handle 6 is a transverse rest 8 the front face of which is rearwardly offset 65 from the front face of the handle 6. Suitably secured to the rest 8 is a resilient retaining member 9 the upper intermediate portion of which extends forwardly. The free outer extremity of this member 9 is 70 downwardly flexed and bears down on the rear portion of the upper side of the blade 5. Intermediately of its width and height the retaining member 9 is so cut that a portion thereof may be bent forwardly to form a spring 10 which exerts downward pressure upon the rear portion of the plate 1; and in the spring 10 slots 11 are formed to receive the plate projections 14.

From the foregoing it is believed that the 80 construction of the razor will be readily understood. The retaining member 9 exerts downward pressure on the blade 5 and holds the latter so that the blade recesses 5a remain engaged by the plate projections 4. The member 9, by its downward pressure, holds the outer extremity of the shank 2 in engagement with the upper face of the handle projection 7. The spring 10 also assists in holding the shank extremity in engagement with the coacting upper face of the projection 7, or, when the blade is removed, holds the shank and handle in engagement, as the retaining member 9 is then rendered inoperative; and further by engagement of the plate 90 projections 14 with the spring slots 11 independent lateral movement of the plate 1 or spring 10 is prevented. It will also be remarked that the shank 2 bearing as it does 95 against the handle 6 for the greater portion 100

of its length assists in forming a rigid structure when the razor is assembled.

While in the foregoing the preferred form of construction has been described and shown it is understood that alterations and modifications may be made therein provided they fall within the scope of the appended claims.

What I claim is:

1. In a razor, the combination of a plate, a shank projecting from one side thereof, a blade resting on the opposite side of said plate, a handle parallel with said shank against which the latter rests for the greater portion of its length, a projection on the outer extremity of said handle, the outer extremity of the shank being adapted to rest against the inner face of said projection, said outer extremity and inner face being in slideable engagement with one another, and a resilient retaining member on said handle the outer extremity of which bears down on said blade holding it against said plate and said shank extremity against the inner face of the handle projection.
2. In a razor, the combination of a plate having forwardly projecting fingers formed along one extremity, a shank projecting from one side thereof, a blade resting against the opposite side thereof with its cutting edge extending partly over said fingers, means holding said blade from sliding on said plate, a handle longitudinally against which said shank rests, a projection on said handle against which the outer end of said shank rests, a resilient retaining member on said handle the outer extremity of which bears down on said blade holding it against said handle projection, and a spring extending from said retaining member exerting pressure against said plate.
3. In a razor, the combination of a plate, a shank projecting from one side thereof, a blade resting against the opposite side of said plate, means holding said blade from sliding on said plate, a handle longitudinally against which said shank rests, a projection on said handle against which the outer end of said shank rests, a resilient retaining member on said handle the outer extremity of which bears down on said blade, a forwardly projecting spring integral with said retaining member which exerts downward pressure against said plate adjacent its rear margin, and projections on said plate engaged by slots formed through said forwardly projecting spring.
4. In a razor, the combination of a plate, a shank projecting from one side thereof, a blade resting on the opposite side of said plate having marginal recesses formed therein, projections on said plate engaging said recesses, a handle longitudinally against which said shank rests, a projection on said handle against which the outer end of said shank rests, the coacting faces of the handle projection

and the shank extremity being so formed as to prevent accidental disengagement of these parts, a transverse rest at one extremity of said handle, a resilient retaining member secured to said rest, the outer extremity of said member bearing down on said blade, a forwardly projecting portion integral with said member having slots therethrough, projections on said plate which engage said slots, and fingers formed along one margin of said plate over a portion of which the cutting edge of the blade projects.
